MANUFACTURE OF GRIDS AND THE LIKE
AND MACHINE THEREFORCyprian A. Narwid, Harrison, N. J., assignor to
Tung-Sol Lamp Works Inc., Newark, N. J., a
corporation of Delaware

Application April 22, 1939, Serial No. 269,399

20 Claims. (Cl. 140—71)

This invention relates to the manufacture of grids for radio tubes and the like, and particularly to a novel method and machine for the manufacture of such grids whereby the bows or bends often found in grids are prevented or controlled.

Grids for use in radio tubes and the like are usually manufactured by notching support wires carried by a relatively rotating mandrel, winding the grid wire into the notches and fastening the grid wire into the notches, as by swaging. The support wires after the notching, winding and swaging operations of conventional practice tend to bend or depart from a perfectly straight position with the result that undesirable bows or bends are formed in the finished grids.

One object of the invention is to control the degree of the bow or bend of the support wires so as to avoid the undesirable bows or bows of the prior practice and to obtain grids approaching the straight or unbent character desired in practice.

Other objects of the invention will hereinafter appear.

For a better understanding of the invention reference may be had to the accompanying drawings forming a part of this application wherein:

Fig. 1 is an end view of a part of a grid machine embodying the invention;

Fig. 2 is a side elevational view thereof, partly in section;

Fig. 3 is a sectional view along the line 3—3 of Fig. 1;

Fig. 4 is a front view of a part of the mechanism;

Fig. 5 is a sectional view along the line 5—5 of Fig. 4;

Fig. 6 is an exploded view of a part of the mechanism;

Fig. 7 is a view indicating the undesirable bend or bow of a grid of conventional practice;

Fig. 8 illustrates the character of the grid which may be obtained according to the present invention;

Fig. 9 is a diagrammatic view indicating the principle of the invention; and

Fig. 10 is a diagrammatic view showing a modification.

Referring to the drawings there is shown a grid machine embodying the conventional notching wheel 1 rotatably mounted in a frame 2, a conventional swaging wheel 3 suitably supported by frame element 4, a conventional spindle 5 mounted in bearings 8 and carrying a mandrel 9, supporting wires 10 and 11 for the grids, and

a reel 12 for supplying the grid wire 13. It is understood that the supply wires 10 and 11 are furnished by a reel which is mounted for rotation with the spindle 5, and also that there is suitable means provided, omitted from the drawings for convenience in illustration, for engaging and drawing the support wires 10 and 11 over or through the mandrel 9. This means is located to the left of Fig. 2 and in line with the grid 1 being manufactured and engaging and pulling the support wires 10 and 11 together with the grid formed thereon towards the left as indicated by the arrow.

These mechanisms operate as in conventional practice to draw the support wires 10 and 11 through the machine, beneath the notching wheel 1, and over the swaging wheel 3. The notching wheel 1 forms the notches indicated in the support wires 10 and 11 (Figs. 7 and 8) for the reception of the grid wire 13. After the positioning of the wire 13 in a notch, the swaging wheel 3 fastens the grid wire firmly to the support wire by the usual swaging operation. The swaging wheel 3 is movable toward and away from the mandrel 9 by a mechanism omitted for convenience in illustration for the purpose of discontinuing at desired intervals the swaging operation. These intervals of non-swaging include the parts where the grid length is severed for use in radio tubes and the like. The mandrel 9 on the one hand and the notching wheel 1 and swaging wheel 3 on the other are relatively rotatable. In the particular embodiment shown the mandrel 9 is carried by the rotating spindle 5 while the notching wheel 1 and the swaging wheel 3 are relatively fixed, though the wheels 1 and 3 are journaled for rotation or oscillation about their respective axes and are adjustable toward and away from the mandrel. As the mandrel 9 is rotated, that part of the support wire which projects above the grooves 9' in the mandrel 9 are engaged by the notching wheel 1 to form the notches, and similarly the swaging wheel 3 engages the support wires at the notches to swage the grid wire 13 into fixed position on the supports.

In the production of grids according to the conventional practice the support wires 10 and 11 tend to bend towards the notched sides with the resultant bow or bend formed in the grid, as indicated slightly exaggerated in Fig. 7, and they also tend to become twisted out of co-planar relation. This renders the grid difficult to mount and assemble and the degree of bow or bend or twist of the grid support wires in the conven-

tional practice cannot be predetermined with any certainty.

Referring to Fig. 2 of the drawings, there is provided a pair of holding rollers 14 which are disposed in advance of the notching wheel 1, which rollers engage the support wires 10 and 11 and hold the same firmly in the grooves 9' of the mandrel 9, as set forth and described in my application Serial No. 212,161, filed June 6, 1938. These rollers 15 are journaled in the ends of the lever arms 17 which are pivotally mounted and supported on a collar 18 fastened to the mandrel 9 or to a member carrying the mandrel 9. These lever arms 17 carry at their other ends adjusting screws 20 which bear upon the mandrel support for adjustment of the pressure exerted by the rollers 15 upon the support wires 10 and 11 disposed in the grooves 9'. Clamping screws 21 are indicated for locking the adjusting screws 20 in their adjusted position. The depth of the grooves 9' in the mandrel or mandrel support are sufficient in the neighborhood of the clamping screws 20 to avoid the latter engaging the support wires 10 and 11, but the wires are exposed 25 to engagement by the rollers 15 and the notching and abrading wheels at the mandrel 9 proper. The mandrel assembly comprises a shaft 25 and an integral reduced extension 27 beyond the ring 26. The latter is adapted to receive a detachable mandrel member 9 which may be fastened thereto in any suitable manner. In the particular structure illustrated, the mandrel 9 is inserted over the extension 27 and is firmly clamped thereto by a screw 28 being screw-threadedly 30 attached to a corresponding screw-threaded opening 28' formed in the extension 27, a collar 29 being provided on the screw 28 to enable the screw to firmly fasten the mandrel 9 to the extension 27 in ring 26 to be carried thereby in a 35 non-rotatable manner. The provision of a detachable mandrel 9 enables mandrels of different diameters and dimensions to be readily substituted for the making of different sizes and types of grids.

40 There is also detachably mounted upon the shaft 25 and extension 27 a bridge or bearing member 30 having grooves 30' therein, through which grooves the grid wires 10 and 11 pass after the grid wire 13 is fastened to the wires 10 and 11 by the notching and abrading wheels. This bridge or bearing member is clamped tightly 45 against the mandrel 9 by the screw 28 and collar 29 but is maintained in spaced relation thereto by means of a sleeve extension 31, this extension, 50 in the particular embodiment shown, being integrally formed with the bridge or bearing member 30. In the embodiment of Figs. 1 to 6 and 9 a pair of wheels or idler rollers 32 are caused to engage the wires 10 and 11 of the formed grids 55 at points on the opposite sides of the bridge or bearing member 30. These wheels 32 and 33 apply to the support wires 10 and 11, as the latter are relatively rotated therewith, bending forces or stresses to the short sections of support wires 10 and 11 disposed therebetween which neutralize 60 and offset the bending tendency of the wires 10 and 11 produced during the wrapping and fastening of the grid wire 13 thereabout. Thus these wheels 32 and 33 in cooperative relation with the 65 bridge or bearing member 30 apply to the wires 10 and 11 progressively as the grids are advanced longitudinally a series of upsetting or neutralizing strains for preventing the bow shown in Fig. 7 and any twist therein and obtaining a straight 70 grid as indicated in Fig. 8. The support wires 10

and 11 in Fig. 8 are also brought into co-planar relationship, so that there is no twist. In Fig. 9 the actual bending is exaggerated in amount, but by engaging the wire at the points on each side of the member 30 to apply radially directed bending or strain upsetting forces the wheel members 32 and 33 do tend to impart to the wire slight bends in an inward direction with the inside of the bends concave, as indicated in Fig. 9. The illustration, however, is exaggerated and instead of imparting to the short section of wire between the wheels 32 and 33 an actual radially inward bend these wheels may merely apply bending forces without actually effecting a bend, or if the wires 10 and 11 are actually curving outwardly, as indicated in Fig. 7, or tending to curve outwardly these rollers 32 and 33 may merely apply sufficient forces on the opposite sides of the member 30 to straighten that short section at the time being engaged by the rollers 32 and 33. The sections of the wires 10 and 11 operated upon by the wheels 32 and 33 at each revolution really overlap because ordinarily the longitudinal feed or advance of the grid wires 10 and 11 for each revolution is less than or may be less than the 25 distance between the rollers 32 and 33. These wheels 32 and 33 are capable of two adjustments, one in a radial direction with respect to the axis of rotation of the spindle and the mandrel 9 and the other with respect to the distance from the 30 member 30, each of the rollers 32 and 33 being independently adjustable. For whatever adjustment may be made the members 32 and 33, in cooperation with the member 30, impart to the wires 10 and 11, after the grid wire 13 is fastened thereto, a series of inwardly bending or straightening forces, applied progressively as the grid advances with the wires 10 and 11 following the holding and guiding grooves 9' and 30', and with the results partly indicated in Fig. 8. The grooves 9' and 30' are preferably of the same radius as the wires 10 and 11. In the embodiment of Figs. 1 to 6 and 9 the bridge or bearing member 30 is illustrated as of the same diameter as the mandrel 9, that is, groove 30' is in line with and on a level with the groove 9' formed in the mandrel 9 and this applies to each side of the mandrel. There are two of each such grooves 9' and 30' shown because the grid being produced is one having two spaced wires 10 and 11 to both of which wires 50 the grid 13 is fastened.

The wheels 32 and 33 for applying the bending or straining forces to the support wire on the opposite sides of the member 30 may be supported in any suitable manner. In the particular embodiment shown they are carried by a bracket unit comprising a U-shaped casting 40, having an arm 41 with fastening slots 42 formed therein for the accommodation of fastening bolts 43, the latter passing through the slots 42 and screw-threadedly attached to the frame of the machine. The bolt slot connection shown provides for a slight adjustment of the casting 40. Each of the rollers 32 and 33 is journaled upon the lower end of a shaft 45 which is carried by a block 46. Each of the shafts 45 and the blocks 46 are identical and a description of one unit will apply to the other unit. Each block is laterally slit or slotted at 47 and 48 and is provided with openings for the reception of supporting pins 47' and 48', the supporting pins 47' and 48' being fixedly carried by the legs of the casting 40. An opening for the pin 47' forms the bottom of the slot 47 and an opening for the pin 48' is formed in line with the slot 48, but the latter extends beyond to 70

an enlargement 49. A screw bolt 50 and a corresponding screw-threaded recess in the block is utilized for clamping the sides of the block, determined by the slot 41, about the pin 47', a slot or slit 52 being provided at right angles to the slot 47 to impart to the jaws formed by the slot 47 a sufficient degree of flexibility to fasten the block firmly to the pin 47'. A similar screw bolt 50 passing downwardly through the block 10 and received in a screw-threaded opening formed therein serves to tighten the lower part of the block firmly against the pin 48'. The shaft 45 passes through an opening in the block and screw-threadedly receives an adjusting nut 54, the latter being disposed in a recess formed in the block. A tightening and locking nut 55 is provided on the upper end of the shaft 45 for the purpose of locking the shaft 45 in any adjusted position. The block is also provided with a slot 20 56 for each of the shafts 45 in which a guide pin or screw 57 fastened to the shaft 45 is disposed for guiding the shaft 45 in a longitudinal direction and for preventing rotary movement thereof. The locking nut 55' for one of the shafts 25 45 is made shorter than the corresponding locking nut 55 of the other shaft for the purpose of effecting a larger clearance between the knurled surfaces thereof. Thus in addition to the adjustment of the whole casting 40 through the slots 42 and bolts 43 there are two additional 30 adjustments for each of the shafts 45, namely, each shaft 45 may be adjusted towards and away from the axis of the spindle and mandrel to apply a greater or smaller bending force at the point of engagement with the support wire as may be desired. This adjustment is effected by releasing the locking nut 55 or 55' and then by rotating the adjusting nut 54 to obtain the desired adjustment whereupon the locking nut 55 or 55' may be 35 screwed home to lock this particular adjustment. Each block 46 may also be adjusted together with its shaft 45 along the supporting pins 47' and 48'. This is effected by releasing the clamping bolts 50 and 51, sliding a block along the pins 47' and 48' to the point desired and then reclamping the 40 block to the supporting pins by screwing bolts 50 and 51 home.

In the embodiment of Fig. 10 there is only a single roller 33 on a shaft 45 carried by a single block 46. In this case the bending or straightening force applying roller 33 engages and applies the desired force to the wires 10 and 11 at a point slightly beyond the bridge or bearing 60. The latter and the grooves 60' in this case are of 45 slightly larger diameter than the corresponding dimensions of the mandrel 9 and its guiding groove 9', but the grooves 9' and 60' are preferably of the same radius, these grooves being in the plane of the axis. The difference in diameter however is exaggerated in Fig. 10 for convenience in illustration. I have obtained particularly good results with the member 60 having a spread or diameter of from .002 to .010 inch greater than that of the mandrel. The wires 10 and 11 are 50 thereby spread outwardly by the member 60 a distance of from .001 to .005 inch for each wire as the wire passes off the mandrel 9 and passes over the member 60. The operation of this embodiment of the invention is substantially the 55 same as that of the mechanism set forth in my above mentioned pending application for letters patent.

Thus by the adjustment of the wheels or rollers 32 and 33 grids controlled as to the straightness desired may be obtained at will and this ap-

plies to both modifications of the invention. With the two rollers 32 and 33 and the bearing member 30 of the same diameter as the mandrel 9 the adjustment is easier and more flexible, although as set forth above and as set forth in my pending application above referred to, satisfactory results are obtained by the use of a single roller 33 and the spreader member 60 of Fig. 10. In either case as the grid support wires 10 and 11 are advanced with the grid wire 13 fastened 10 thereabout a succession of inwardly directed bending or straightening forces or stresses tending to give a straightening effect are applied to the grid support wires at a point or points beyond the mandrel, and progressively, with the 15 result that the bending strains or forces imparted to the wires by the notching and grid wire fastening means are neutralized or offset to any degree that may be desired. A straight grid may be thus obtained.

I claim:

1. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes and means for progressively applying pressure inwardly on the support wire at points beyond the mandrel and on opposite sides of the bearing member as the support wire advances.

2. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes and means for progressively applying pressure inwardly on the wire at a point beyond the mandrel and on one side of said bearing member as the support wire advances.

3. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes, and means for progressively applying pressure inwardly on the support wire at a point beyond the mandrel and the bearing member but closely adjacent to the latter.

4. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes and idler rollers for progressively applying pressure inwardly on the support wire at points beyond the mandrel and on opposite sides of the bearing member as the support wire advances.

5. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes and an idler roller for progressively applying pressure inwardly on the wire at a point be-

yond the mandrel and on one side of said bearing member as the support advances.

6. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes and means for progressively applying pressure inwardly on the support wire at points beyond the mandrel and on opposite sides of the bearing member as the support wire advances, said bearing member being of the same radial dimensions as those of the mandrel.

15 7. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes and means for progressively applying pressure inwardly on the wire at a point beyond the mandrel and on one side of said bearing member as the support advances, said bearing member being of the same radial dimensions as those of the mandrel.

20 8. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes and an idler roller for progressively applying pressure inwardly on the wire at a point beyond the mandrel and on one side of said bearing member as the support advances, said idler

25 roller being universally adjustable.

9. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes and an idler roller for progressively applying pressure inwardly on the wire at a point beyond the mandrel and on one side of said bearing member as the support wire advances, said idler roller being adjustably mounted to vary the spacing between the roller and the bearing member and to vary the pressure to be applied to the support wire.

30 10. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes and an idler roller for progressively applying pressure inwardly on the wire at a point beyond the mandrel and on one side of said bearing member as the support wire advances, said idler roller being carried by a shaft which is longitudinally adjustable to adjust the pressure to be applied to the support wire at a point beyond the mandrel and on one side of said bearing member as the support wire advances, said shaft being mounted on a block which is mounted for adjustment at right angles to the other adjustment.

35 11. In a grid machine of the character set forth comprising a relatively rotatable mandrel and grid wire fastening means and means for feeding

support wire along the mandrel and for feeding grid wire thereto, the provision at a point beyond the mandrel of a bearing member over which the support wire with the grid wire fastened thereto passes and idler rollers for progressively applying pressure inwardly on the support wire at points beyond the mandrel and on opposite sides of the bearing member as the support wire advances, each of said idler rollers being adjustable independently of the other to vary the spacing thereof from said bearing member and to vary the pressure to be applied to the support wire.

40 12. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire passes after the grid wire has been fastened to the support wire and means for progressively applying pressure inwardly on the support wire at points beyond the mandrel and on opposite sides of the bearing member comprising a pair of independently adjustably mounted carrying frames, an adjustable shaft carried in each of said frames, and idler rollers carried by the ends of said shafts for engaging said support wire at each revolution.

45 13. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes and an idler roller for progressively applying pressure inwardly on the wire at a point beyond the mandrel and on one side of said bearing member as the support advances, said idler roller being journaled on a longitudinally adjustable shaft and said shaft being carried by a block which is adjustably mounted upon a bracket, said block having an opening therethrough for the reception of a support rod and being slotted in the plane of the opening together with a clamping bolt for clamping the opposite sides of the slot against the support.

50 14. In a grid machine of the character set forth comprising a relatively rotatable mandrel and grid wire fastening means and means for feeding support wire along the mandrel and for feeding grid wire thereto, the provision at a point beyond the mandrel of a bearing member over which the support wire with the grid wire fastened thereto passes and means for progressively applying pressure inwardly on the wire at a point beyond the mandrel and on one side of said bearing member as the support wire advances, said bearing member being detachably mounted adjacent the end of said mandrel.

55 15. In a machine of the character set forth in claim 2 wherein the end of the mandrel is detachably mounted upon a spindle and said bearing member is detachably mounted adjacent said mandrel.

60 16. In the manufacture of grids by notching support wire and fastening grid wire thereto by abrading operations, the method which consists in progressively applying inwardly bending stresses at fixed intervals to the support wire after the grid wire is fastened thereto.

65 17. In a grid machine of the character set forth in claim 2 wherein the mandrel and the bearing member are provided with grooves of substan-

tially the same radius as that of the support wire for holding and guiding the support wire past the grid wire fastening means and the pressure applying means.

- 5 18. In a grid machine of the character set forth in claim 1 wherein the mandrel and the bearing member are provided with grooves of substantially the same radius as that of the support wire for holding and guiding the support
- 10 10. wire past the grid wire fastening means and the pressure applying means.
- 15 19. In a grid machine of the character set forth, comprising relatively rotatable mandrel and notching means and means for feeding support wire along the mandrel and for feeding grid wire to the notches formed by the notching means, the

provision of means for exerting pressure against the support wire radially of the mandrel at points both in advance of and beyond the notching means.

20. In a grid machine of the character set forth, comprising relatively rotatable mandrel and notching means and means for feeding support wire along the mandrel and for feeding grid wire to the notches formed by the notching means, the provision of means positioned in advance of the notching means for pressing the support wires inwardly against the mandrel and means beyond the notching means for exerting an oppositely directed pressure upon the support wires.

CYPRIAN A. NARWID.
